CATHODE-RAY PROJECTION TUBE

Homer G. Boyle, Dobbs Ferry, N. Y., assignor, by
mesne assignments, to Philips Laboratories,
Inc., Irvington on Hudson, N. Y., a corporation
of Delaware.

Application August 18, 1944, Serial No. 550,077

12 Claims. (Cl. 250—164)

1

This invention relates to cathode ray tubes, and more particularly to cathode ray projection systems for use in television and the like.

An object of the present invention is to provide a cathode ray tube incorporating a projection system.

Another object of the invention is to provide a cathode ray projection tube having a higher light output than existing cathode ray projection systems.

A further object of the invention is to combine a cathode ray tube and a projection system into one integral unit so as to permanently align one with the other.

Still another object of the invention is to provide a cathode ray projection tube with an accelerator ring forming part of the lens system.

A still further object of the invention is to provide a cathode ray projection tube with an accelerator ring forming part of the gun structure.

Yet another object of the invention is to provide a cathode ray projection tube incorporating cooling means as part of the integral projection tube structure.

Other objects, and the manner in which the same are obtained, will appear from the following description.

An outstanding problem in cathode ray projection is that of obtaining maximum light output. Closely interwoven with this are problems of electron acceleration, to impart sufficient energy to the electrons; of screen arrangement, to obtain optimum energy translation in the screen; of screen cooling, to avoid energy losses and shortening of the life of the screen due to overheating, and of optical projection, to minimize light losses during passage of the light rays through the optical lens system. Past attempts at a solution of the center problem have failed, it seems, for the reason that improvements of some of these factors were obtained to the detriment of the others, with the result that in the end the main problem of obtaining maximum light output was hardly nearer to solution than before.

The present invention contemplates solving this problem, and thereby obtaining a light output several times that heretofore obtainable, by providing a cathode ray tube incorporating a projection system as part of the integral tube structure, and similarly incorporating with this structure accelerating and, if desired, also cooling means so that the whole forms a unified assembly.

A suitable embodiment of the invention is a cathode ray projection tube including, in addition

2

to a standard type gun structure designed for customary basing and assembly methods, a bulbous envelope portion with a rear wall mounting a reflector surface and forming a spherical mirror, and a front wall mounting, in its center, a fluorescent screen facing the gun structure, while a corrector plate correcting for the spherical aberration of the mirror is arranged in the part of the front wall surrounding the screen so mirror and plate combine to act as a Schmidt lens system of great gathering power, high aperture and small focal ratio. According to a preferred embodiment of the invention, the part of the front wall surrounding the screen, itself forms the corrector plate; as an alternative, this part may mount a corrector plate preferably made of plastic and intimately joined to this part so that in either case, the Schmidt lens system forms part of the integral cathode ray tube structure, according to the basic concept of the invention.

Two accelerator rings are contemplated for post deflection acceleration of the electrons originating in the gun, one being mounted on extensions of the gun's structural members extending into the bulbous envelope portion while for the other, according to a preferred embodiment of the invention, the metallic reflector surface on the rear wall of the bulbous envelope portion may be utilized. As an alternative, a second accelerator ring may be mounted on the gun structure in proximity to the reflector surface.

The center of the front wall mounting the screen is dropped relative to the plane of the surrounding part of the front wall forming or mounting the corrector plate to provide tubes, and particularly tubes of extremely high brilliance and power with a cooling space for the screen which thus is incorporated in the integral tube structure the same as are the projection system and the accelerating rings.

In the drawings affixed to this specification and forming part thereof several embodiments of the invention are illustrated diagrammatically by way of example.

In the drawings,

Fig. 1 is a diagrammatic side view, with some parts shown in perspective and others broken away for clarity, of a cathode ray projection tube being a preferred embodiment of the invention;

Fig. 2 is a similar showing of a modification of a detail of Fig. 1;

Fig. 3 is a similar showing of a modification of another detail of Fig. 1; and

Fig. 4 shows a modification of still another detail of Fig. 1.

Referring now to the drawing wherein like elements are denoted by identical reference numerals, and first to Fig. 1, the cathode ray projection tube according to the invention is seen to include a base 1, a gun structure 2 and an envelope generally indicated at 3 and comprising a neck 4 and a bulbous portion 5.

The bulbous envelope portion 5 has a rear wall 6 with an opening 7 surrounded by a flange 8 by which portion 5 is joined to the neck 4. The rear wall 6 is so shaped and so coated with a metallic coating 9 of silver or aluminum, for example, as to form a spherical mirror generally indicated at 10, the coating being disposed on that side of the rear wall facing the interior of the portion 5. The bulbous portion 5 also has a front wall generally indicated at 11 and including a dropped center portion 12 mounting a fluorescent screen 13 and defining a cavity 14 open toward the outside and serving as a cooling space; a marginal portion 15 formed as a corrector plate to correct for the spherical aberration of the mirror 10; and a seal 16.

Structural members 17 of insulating material, mounted on the gun structure 2 and extending into the bulbous envelope portion 5, mount an accelerator ring 18 which by a wire 19, is connected with a high voltage connector 20 provided on the bulbous portion 5.

In the preferred embodiment of the invention according to Fig. 1, the reflector coating 9 is utilized as an additional accelerator ring, by connecting it, through a wire 21, to another high voltage connector 22 arranged on the neck 4. In this instance, the coating 9 is thus imparted a double function as a reflector as well as an accelerator means.

As shown in Fig. 2, the front wall of the bulbous envelope portion 5 surrounding the screen 13, instead of being itself formed as the corrector plate, may be provided as an extension 5' of the bulbous envelope 5 and mount a corrector plate 15' preferably made of plastic and intimately joined to part 5' so as to be part of the integral tube structure.

As an alternative to the utilization of the reflector coating 9 as an accelerator ring, the embodiment of the invention according to Fig. 3 includes another individual accelerator ring 23 mounted on the structural members 17 the same as the accelerator ring 18 but nearer to the gun structure 2 and, for example, in proximity to the reflector surface 9, and connected through a wire 24 to high voltage connector 22 on neck 4.

In tubes of extremely high brilliance and power, it is advisable to cool the screen by water cooling, for example, to avoid overheating and consequent shortening of the life of the screen and reduction in the light output thereof. Fig. 4 illustrates a modification of the invention where the space 14 serves as a cooling space for liquid cooling medium which is supplied through inlet 25 and discharged through outlet 26, a cover 27 closing the space 14 to seal the cooling chamber.

In the operation of the invention, a beam of electrons generated and deflected in the electron gun 2 according to conventional practice, is accelerated either by reflector surface 9 acting as accelerator ring 23 (Fig. 1) or the individual accelerator ring 23 (Fig. 3) and further accelerated by accelerator ring 18, to impinge on the target or fluorescent screen 13 where its energy is translated into visible intensity. The light rays thus generated are reflected by the coating 9, now acting as reflector surface, of the spherical mirror

10 and passed on to the corrector plate 15 or 15' through which they leave the tube.

The present invention results in numerous advantages. Not only is the fluorescent screen viewed from the rear, thus obviating the necessity of viewing through the crystals of the screen with its attendant light losses, and not only is the light intensity thus obtained passed through a Schmidt lens system of great gathering power, high aperture, and small focal ratio which is inherently a wide angle lens system so large magnification is obtained over comparatively short projection distances, but moreover, light losses are reduced to a minimum by the elimination of glass surfaces and air space between surfaces. According to the preferred embodiment of the invention, there is no glass bulb in the light path to cause refraction and attendant light losses, and even where, as in the modification of Fig. 2, a single glass portion in the light path is retained in return for maximum economy of manufacture, the sacrifice in light output is held to a minimum. The light rays leaving the screen travel in vacuo where they are not subject to diffusion by foreign particles as they would be in air, with the result that the light rays leave the tube and enter air in substantially straight lines. In this manner, a light output several times that of the most advanced cathode ray projection systems is obtained.

The incorporation of the projection system in the cathode ray tube to form an integral unit, results in additional important advantages, such as the permanently fixed alignment of the projection system with respect to all tube elements such as gun and screen, and the economy of utilizing the mirror for the rear wall, and the screen for part of the front wall of the bulbous tube portion. Other major advantages include the combination of accelerating rings with the lens system; the use of the reflector surface as accelerating ring to simplify the structure and further unify the assembly; and the incorporation of cooling means for the screen as part of the integral tube structure.

I wish it to be understood that I do not desire to be limited to the exact details of construction, design and operation shown and described as various modifications within the scope of the appended claims may occur to a person skilled in the art.

I claim:

1. A cathode ray projection tube comprising an electron gun, a bulbous envelope portion, a fluorescent screen, a spherical mirror and a corrector plate for spherical aberration, said corrector plate surrounding said screen and forming part of the front wall of said portion.
2. A cathode ray projection tube comprising an electron gun, a bulbous envelope portion, a spherical mirror forming the rear wall of said portion, and a fluorescent screen and a corrector plate for spherical aberration surrounding said screen, in the front wall of said portion.
3. A cathode ray projection tube comprising an electron gun, a bulbous envelope portion, a rear wall in said portion forming a spherical mirror, and a front wall in said portion comprising a marginal part forming a corrector plate for spherical aberration, and a dropped center part mounting a fluorescent screen inside said portion and defining a cavity on the outside of said portion.
4. A cathode ray projection tube comprising an electron gun, a bulbous envelope portion, a rear

wall in said portion forming a spherical mirror, and a front wall in said portion comprising a marginal part mounting a corrector plate for spherical aberration, and a dropped center part mounting a fluorescent screen inside said portion and defining a cavity on the outside of said portion.

5. A cathode ray projection tube comprising an electron gun, a bulbous envelope portion, a rear wall in said portion forming a spherical mirror, and a front wall in said portion comprising a marginal part including a corrector plate for spherical aberration, a dropped center part mounting a fluorescent screen inside said portion and defining a cavity on the outside of said portion, and cooling means extending into said cavity.

6. A cathode ray projection tube comprising an electron gun, a bulbous envelope portion, a rear wall in said portion forming a spherical mirror, and a front wall in said portion comprising a marginal part including a corrector plate for spherical aberration, a dropped center part mounting a fluorescent screen inside said portion and defining a cavity on the outside of said portion, a cover sealing said cavity and cooling means extending through said cover into said cavity.

7. A cathode ray projection tube having an envelope comprising a neck and a bulbous portion, a spherical mirror forming the rear wall, and a fluorescent screen and a corrector plate for spherical aberration surrounding said screen, in the front wall of said bulbous portion, an electron gun including structural members in said neck, extensions mounted on said structural members and extending into said bulbous portion, and an accelerator ring mounted on said extensions.

8. A cathode ray projection tube having an envelope comprising a neck and a bulbous portion, a spherical mirror having a metallic coating and forming the rear wall, and a fluorescent screen and a corrector plate for spherical aberration surrounding said screen, in the front wall of said bulbous portion, an electron gun including structural members in said neck, extensions mounted on said structural members and extending into said bulbous portion, an accelerator ring mounted on said extensions, and a high voltage connection leading to said coating to adapt the same for use as an additional accelerator ring.

9. A cathode ray projection tube having an envelope comprising a neck and a bulbous portion, a spherical mirror forming the rear wall, and a fluorescent screen and a corrector plate for spherical aberration surrounding said screen, in the front wall of said bulbous portion, an elec-

tron gun including structural members in said neck, extensions mounted on said structural members and extending into said bulbous portion, an accelerator ring mounted on the ends of said extensions, and an additional accelerator ring mounted on said extensions in proximity to said mirror.

10. A cathode ray projection tube having an envelope comprising a neck and a bulbous portion, an electron gun in said neck portion, a spherical mirror forming the rear wall of said bulbous portion, and a fluorescent screen and a corrector plate for spherical aberration surrounding said screen forming the front wall of said bulbous portion.

11. A cathode ray projection tube comprising a neck portion and a bulbous envelope portion, a rear wall in said bulbous portion having a shape and a metallic coating such as to form a spherical mirror, a high voltage connection leading to said coating, a fluorescent screen in said bulbous portion and spaced from said coating, an accelerator ring within said bulbous portion between said fluorescent screen and said coating, and a high voltage connection leading to said ring.

12. A cathode ray projection tube comprising a neck portion and a bulbous envelope portion, an electron gun including structural members in said neck portion, a rear wall in said bulbous portion having a shape and a metallic coating such as to form a spherical mirror, a high voltage connection leading to said coating, a fluorescent screen in said bulbous portion and spaced from said coating, extensions mounted on said structural members, and an accelerator ring mounted on said extensions.
